UNITED STATES PATENT OFFICE.

GUS A. VOLBY, OF WENTWORTH, SOUTH DAKOTA.

SPARK-ARRESTER.

No. 876,417.

Specification of Letters Patent.

Patented Jan. 14, 1908.

Application filed January 28, 1907. Serial No. 354,466.

To all whom it may concern:

Be it known that I, GUS A. VOLBY, a citizen of the United States, residing at Wentworth, in the county of Lake and State of 5 South Dakota, have invented a new and useful Spark-Arrester, of which the following is a specification.

This invention relates to spark arresters for the smoke stacks of locomotives, traction engines, and the like and its object is 10 to provide a device of this character which is simple, durable and inexpensive in construction and which will not interfere with the draft through the stack.

15 A still further object is to provide a spark arrester which will automatically assume such a position as to cause the wind to blow the sparks and cinders thereinto.

With these and other objects in view the 20 invention consists of certain novel features of construction and combinations of parts which will be hereinafter more fully described and pointed out in the claims.

In the accompanying drawing, which is a 25 perspective view of the device in position upon a stack, the preferred form of the invention has been shown.

Referring to the figures by characters of reference, 1 is a stack having an annular 30 flange 2 near the upper end thereof which serves to support a ring 3 loosely surrounding the stack and designed to rotate freely thereon. This ring may if desired be split as shown and provided with out-turned ears 35 4 clamped together by means of a bolt 5. In order to improve the construction of the ring it is important that the same be free to rotate upon the stack. Extending upward from the ring 3 and secured thereto in any preferred 40 manner is a skeleton frame consisting of spaced bowed wires 6 and 7 connected at their lower ends, as shown at 8 and projecting from the rear bow 7 at the lower end thereof is a horizontally extending loop 9. The 45 frame formed by the two bows 6 and 7 and the loop 9 is covered except at the front thereof by a wire fabric hood 10 and a wire fabric can be secured within the loop 9 so that a compartment is formed within the hood 50 and in rear of the stack for the reception of cinders, etc. Instead of providing a wire fabric within the loop 9 a plate may be used. In either event an opening 11 is formed about 55 which is secured a depending outlet pipe 12.

It is to be noted that the front bow 6 of

the hood is curved forward so as to overhang the stack.

By providing a locomotive or traction engine stack with an arrester such as herein described a portion of the products of combustion upon leaving the stack will enter the hood 10 and the gaseous products will pass through the hood while the cinders will be retained thereby. A portion of the products of combustion will not enter the hood but 60 any cinders which may be carried upward with this portion of the escaping products will be driven back into the hood by the current of air established by the forward movement of the engine. As the entire hood is 65 placed back of the axis of the ring 3 it is apparent that the pressure of the wind thereagainst will always maintain the hood in position upon the rear portion of the stack. If the engine is not in motion the hood will be 70 maintained in proper position by any wind 75 which may be blowing.

It will be understood that the cinders will be deflected by the hood into the rear compartment within the device from which they 80 will pass downward to the pipe 12. This pipe may conduct the cinders to any point desired but it must necessarily be connected only to the hood so that the rotation of the hood will not be interfered with.

It will be seen that this device is very 85 simple, durable and inexpensive in construction, can be readily attached to a stack and constitutes an efficient means for collecting the cinders as they escape from the stack.

It will be noted that the hood 9 is disposed 90 below the upper end of the stack and therefore the upper portion of the stack and the adjoining part of the hood form a receptacle for holding the cinders after they have been 95 caught by the hood and deflected rearwardly.

What is claimed is:

1. The combination with a stack having an annular supporting flange; of a split ring 100 rotatably mounted upon the stack and bearing upon the flange, a supporting bow extending from opposite portions of the ring and over the end of the stack, said bow being curved so as to overhang the stack, a loop extending horizontally from the ring, a fabric hood supported by the bow and ring, said hood overhanging the end of the stack and leaving opposite portions of said stack exposed, a fabric bottom upon the horizontal bow, and an outlet tube extending from said 105 110

bottom, said bottom being disposed below the end of the stack whereby a spark receiving receptacle is produced within the hood.

2. The combination with a stack having 5 an annular supporting flange; of a ring revolvably mounted upon the flange and stack, a fabric hood extending from the ring and disposed to overhang the stack, said hood having a bottom portion beyond and below the 10 upper edge of the stack, said portion consti-

tuting a spark receptacle and said stack extending throughout the width, and constituting one wall, of the spark receptacle.

In testimony that I claim the foregoing as my own, I have hereto affixed my signature 15 in the presence of two witnesses.

GUS A. VOLBY.
